UNITED STATES PATENT OFFICE.

LOUIS D. FORBES, OF BERLIN, ASSIGNOR TO THE BERLIN MACHINE WORKS,
OF BELOIT, WISCONSIN.

ABRADING-CYLINDER.

SPECIFICATION forming part of Letters Patent No. 425,376, dated April 8, 1890.

Application filed August 8, 1889. Serial No. 320,180. (No model.)

To all whom it may concern:

Be it known that I, LOUIS D. FORBES, of Berlin, in the county of Green Lake and State of Wisconsin, have invented a new and useful Improvement in Abrading-Cylinders, of which the following is a specification.

In the annexed drawings, making a part of this specification, Figure 1 is a perspective view of a section of the paper-cylinder. Fig. 2 is an end elevation of the same section. Fig. 3 is an elevation of the cylinder broken away to show a central section of part thereof; Fig. 4, a similar elevation and section, but on a different plane, so that the heads do not hide the stems attached to the clamping-bar. Fig. 5 is a side elevation of the clamping-bar and stems. Fig. 6 is an end elevation of the same; and Fig. 7 is a perspective view of a section of the cylinder, showing a variation 20 in the construction of parts.

The same letters are employed in all the figures in the indication of identical parts.

My invention relates especially to a combination of parts connected with the sand-cylinder of a machine for polishing wood or other surfaces, by means of which the sheet of sand-paper or its equivalent covering the cylinder is attached thereto.

The cylinder A is the usual and well-known 30 cylinder to which the sand-paper is attached. The paper is in large sheets and cut so as to fit the entire periphery of the working part of the cylinder which it encircles, the two ends being received in a longitudinal recess A². The heads of the cylinder are shown at A'. In the case illustrated there is one at each end and one in the middle.

In the bottom of the recess A² is placed a cushion C, which may be a strip of elastic 40 material, preferably an india-rubber or leather strip. A solid piece of an elastic substance may be used, the important feature being that it shall be a substance which will form a cushion capable of indentation under pressure and with sufficient elasticity to resume its original shape when relieved of the pressure. This cushion, it will be observed, is an independent piece of elastic material and not a part of the thin cushion which surrounds

the cylinder under the sand-paper, which is 50 generally secured by nails driven into a piece of wood forming the bottom of the recess, and is too thin to have the amount of compressibility and elasticity required for such a cushion as I desire to use. 55

Above the cushion is an adjustable clamping-bar D, which is capable of being forced down by suitable mechanism to press upon the two ends of the sheet of sand-paper or its equivalent and confine them between the adjustable clamp and the cushion. This is, preferably, a semi-cylindrical bar carried upon stems D', each with a slot D² cut, as shown, and passing down through holes in the bottom of the recess. The clamp is actuated by 60 means of a reciprocating slide E, which is a metal bar sliding in metallic ways E² in the heads, which confine it in place and sustain the upward pressure, the lower edge being restrained by the bottom of the slot formed in 65 bosses G on the exterior or interior surface of the heads. 70

The reciprocating slide E (shown in Fig. 1) has a portion cut away, as shown at E', so as to form wedge-shaped hooks E², which, entering the slots D² in the stems D', bear by their lower faces against the lower ends of the slots D², which slots are preferably beveled at the bottom to conform to the lower edge of the wedges, so that as the slide is drawn to the 75 right from the position shown in Fig. 1 the wedges E², entering the slots D², will cause the stems D' and the clamping-bar D to be drawn down, and so confine the two ends of the sand-paper. When the slide is moved in the opposite direction, the lower surfaces of the cut-away portion E' bear against the lower end of the stems and lift the clamping-bar. In the drawings only one of the hooks is shown. It must be understood that the slide is similarly constructed whenever it is intended to act upon a stem, three being shown in the drawings; but more or less may be used. This reciprocating slide E is actuated by a rod F, screw-threaded at F², which rotates in suitable bearings in the heads A', and is turned by a socket-wrench on the squared ends F', or in other convenient manner. The screw- 85 90 95

threaded portion of this rod passes through a lug or bracket E^4 , attached to the slide E , which has a hole formed with a female screw to receive it. By turning the rod F the reciprocating slide E will be moved in one direction to draw down the clamping-bar D upon the ends of the paper and be moved in the other to raise the clamping-bar and release the ends of the paper.

10 The reciprocating slide shown in Fig. 7 is another and equivalent construction. In that instance the reciprocating slide E has two triangular notches cut out of its upper and lower edges, having an inclined neck E^5 , which passes through the lower end of the slot D^2 , and as the reciprocating slide is drawn to the right, as before, the clamping-bar D is drawn down. When the slide is moved in the opposite direction, the upper 20 surface of the neck E^5 , bearing against a pin D^3 , passing through stem D' and across the slot D^2 , lifts the stem and clamping-bar. As the slot D^2 must be long enough to receive the full width of the slide E , in order 25 to permit the slide to be put in place in constructing the cylinder, when it has thus been put in place the pin D^3 is inserted. This slot D^2 need not be so long when the wedges shown in Fig. 1 are used, because in such 30 case in constructing the cylinder the clamping-bar and its stems may be put in place after the slide E is in place, as then the lower ends of the stems are received in the upper ends of the cut-away portion E' , Fig. 1.

35 It is difficult with the cylinder heretofore in use, to put the sand-paper on so as to have it perfectly uniform upon the cylinder. In this case, however, as the pressure comes upon the paper gradually by reason of the 40 gradual compression of the cushion C , the paper will be drawn endwise, in case there is an inequality of strain upon it, until the strain is equalized along the entire width, and then, when the clamping-bar is drawn 45 down to its bearings, it will hold it firmly and with an equal strain on all parts, so it will be in contact with the cylinder closely upon the whole of its periphery.

What I claim as my invention, and desire to secure by Letters Patent, is—

1. In combination with a sand-cylinder constructed with a recess and an adjustable clamping-bar, an independent elastic cushion in the bottom of the recess for confining the ends of the sand-paper, substantially as set forth.

2. In combination with the adjustable clamping-bar and stems attached thereto, a reciprocating slide which acts upon the stems and actuates the clamping-bar equally and uniformly along its entire length, substantially as set forth.

3. In combination with the recessed cylinder, clamping-bar, and stems attached thereto, and cushion, the adjustable slide with inclined surfaces which act against the stems and gradually close the clamping-bar upon the paper confined between it and the cushion, substantially as set forth.

4. In combination with the adjustable clamping-bar and stems, the slide formed with inclined surfaces which act upon the stems and the screw-threaded rod which gives movement in either direction to the slide, substantially as set forth.

5. The combination of the adjustable clamping-bar and slotted stems attached thereto, the reciprocating slide E , constructed with wedge-formed hooks which enter the slots and draw down the clamping-bars, substantially as set forth.

6. In combination with the adjustable clamping-bar and stems attached thereto, the reciprocating slide E , constructed with an inclined surface which lifts the stems and clamping-bar when the slide is moved to raise the latter, substantially as set forth.

In testimony whereof I have hereunto attached my signature, this 27th day of July, A. D. 1889, in presence of two subscribing witnesses.

LOUIS D. FORBES.

In presence of—
R. MASON,
K. KOEHRIG.
